DRIVING MECHANISM FOR ONE REVOLUTION CLUTCHES

Frank Bycroft Keall, Leicester, England, assignor to United Shoe Machinery Corporation, Flemington, N. J., a corporation of New Jersey

Application April 4, 1946, Serial No. 659,566
In Great Britain April 11, 1945

6 Claims. (Cl. 192—26)

1

This invention relates to driving mechanism and is herein illustrated as embodied in a press of the type disclosed in United States Letters Patent No. 921,503, granted on May 11, 1909, upon an application filed in the name of Arthur Bates.

Presses of the type referred to commonly comprise an arm mounted upon a vertical spindle for movement laterally over a cutting block and for movement heightwise of the cutting block in performing pressure applying operations upon dies positioned upon material located upon the block for producing blanks from the material. The spindle of such a machine is operated from a drive shaft arranged to be connected to a flywheel by a one-revolution clutch. It is an object of the present invention to provide improved driving mechanism for machines of this type which, while effective to drive the shaft positively thus to insure completely cutting through sheet material upon the action of the arm upon a die, will be capable of starting the shaft from rest without undue shock or noise.

To this end and as shown, there is provided a press having a drive shaft and a flywheel together with a yieldable block associated with the flywheel and arranged to be movable with the flywheel into engagement with a clutch part upon the drive shaft when a starting operation is initiated, the block being arranged to yield upon initial contact with the clutch part in such manner as to cushion the shock of engagement of the parts and then to move into engagement with a relatively fixed portion of the flywheel so that the drive shaft will be positively driven.

These and other features of the invention are disclosed in the following specification and in the accompanying drawings and are pointed out in the claims.

In the drawing, the figure is an end view, partly in section, of a portion of the flywheel and clutch mechanism of a press illustrating one embodiment of the invention.

By way of example the drawing illustrates the invention as applied to clutch mechanism for use in machines of the press type such as that disclosed in the aforementioned United States Letters Patent.

The mechanism shown comprises a drive shaft 12 having a hub 14 and a flywheel 16 which is arranged to drive the shaft through mechanism hereinafter described.

To this end, the hub has a recess 18 in which is positioned a clutch bolt 20 slidably mounted for movement at right angles to a radius of the shaft. The clutch bolt is normally forced out-

2

wardly by a spring 22 and is controlled by a tripping mechanism, not shown in detail, and including a cam 24. Any suitable tripping mechanism may be employed, the only requirements being that there be provision for moving the cam into the dotted line position shown for the purpose of engaging the outer end of the bolt 20 to move it into inoperative position after a single revolution of the shaft 12 and for moving the cam 10 outwardly to release the bolt in initiating operation of the mechanism. For example, one tripping mechanism which could be employed is that disclosed in United States Letters Patent No. 1,615,617, granted January 25, 1927, upon application filed in the name of W. A. D'Arcy.

In order to drive the shaft at the proper time the flywheel is provided with mechanism movable into engagement with a face 26 on the bolt. This mechanism comprises a block 28 slidably mounted in a segmental housing 30 secured by bolts 31 to the flywheel. The block has a face 32 arranged to engage the face 26 of the bolt and circumferentially arranged faces 34 arranged slidably to engage the inner surface of a rim 36 forming part of the housing and constituting a guide member for directing the block angularly about the axis of the flywheel. Movement of the block 28 in a counterclockwise direction is limited by engagement of a flat surface 38 on a recessed portion of the block with a stop 40 projecting from the housing of the flywheel.

The block 28 is normally pressed against a stop 41 on the housing by a toggle comprising a heavy spring 42 one end of which is seated in a bore 44 in the block and the other end of which is supported by a shouldered stem piece 46 having a reduced portion 48 resting upon a pin 50 mounted in a recess 52 in a lever 54 which in turn is pivoted upon a stud 56 on the flywheel. A light tension spring 58 connected between a hook 60 on the lever 54 and a pin 62 on the flywheel limits outward movement of the lever 54 about its pivot 56.

Mounted upon the frame of the machine so as to be stationary with respect to the flywheel 16 is a stud 64 carrying a roller 66 and slightly spaced therefrom is a cam plate 68 forming part of the frame. The lever 54 has an outer curved nose portion 70 arranged to engage the roll 66 at the end of a revolution of the flywheel, with the result that the lever is rotated inwardly about its pivot 56, causing the spring to force the block 28 against the stop 41. The cam 68 is shaped to permit gradual outward movement of the lever after it passes off the roll 66, thus to reduce the pressure of the spring 42 upon the block so that the latter is free to move toward the stop 40.

The drawing shows the mechanism with the parts in the position in which the bolt 20 has just been released by the cam 24 and has been thrust by the spring 22 into the path of movement of the block 28 rotating with the flywheel in a clockwise direction, the face 32 of the block having just contacted with the face 26 of the bolt. The shock of engagement of the moving block with the bolt 20 is cushioned by the spring 42 which is compressed as the block moves relatively to the flywheel until the face 38 on the block contacts with the stop 40 on the housing. During the movement of the block relatively to the flywheel, friction will be set up between the faces 34 on the block and rim 36 on the housing, tending further to cushion the shock of engagement. When the lever 54 passes off the roller 66 and then along the cam plate 68, the spring 42 pushes the lever 54 gradually outwardly of the flywheel against the pull of the light spring 58. The tendency of the spring 42 to react suddenly, causing chatter between the block 28 and the bolt 20, is thus eliminated and the driving force of the flywheel upon the bolt 20 will be continued through the block 28 with the face 38 of the block and face 40 of the housing in contact, thus constituting a positive drive. At the end of a revolution of the flywheel and shaft, the bolt 20 will automatically be withdrawn by operation of the cam 24, and the lever 54 will have been brought around so that its curved end portion 70 will again engage the roller 66 and cause the lever to be pressed inwardly by the roller into the position shown in the drawing, the return of the various parts to the positions shown being aided by the spring 58.

Thus it will be seen that the mechanism above described will operate to facilitate connection between a stationary shaft and a rotating flywheel with an initial yielding of parts followed by a positive drive of the shaft by the flywheel.

Having described my invention, what I claim as new and desire to secure by Letters Patent of the United States is:

1. In a one revolution type driving mechanism, a drive shaft, a hub on the shaft, a flywheel mounted coaxially of the shaft, a housing secured to the flywheel and extending circumferentially of the hub, a block slidably mounted in the housing, a clutch part mounted in the hub and movable outwardly thereof into the path of movement of the block, the block having a face for engaging the clutch part and having two oppositely disposed faces, the housing having two stops disposed on opposite sides of the block and arranged to be engaged by said oppositely disposed faces, a resilient means normally operative to force the block against one of the stops in a direction toward the clutch part, and means for releasing the resilient means to provide for the positive engagement of the block with the other stop after the block has engaged the clutch part.

2. In a one revolution type driving mechanism, a drive shaft, a hub on the shaft, a flywheel mounted coaxially of the shaft, a housing carried by the flywheel and arranged circumferentially of the shaft, a block slidably mounted in the housing, a clutch part slidably mounted in the hub for movement into the path of movement of the block, a lever pivotally carried by the flywheel, a spring extending from one end of the lever into engagement with the block and normally operative to force the block in a clockwise direction, means operable upon rotation of the

flywheel to release the pressure of the spring, thereby to provide for movement of the block in a counterclockwise direction relative to the housing, and means associated with the flywheel for positively arresting counterclockwise movement of the block.

3. In a one revolution type driving mechanism, a drive shaft, a hub on the shaft, a flywheel mounted coaxially of the shaft, a plurality of spaced stops carried by the flywheel, a block slidably mounted upon the flywheel for movement between the stops, a clutch part slidably mounted in the hub for movement into the path of movement of the block, a spring-pressed toggle pivotally mounted upon the flywheel and having one end thereof connected to the block for forcing the block toward one of the stops, a cam for maintaining the toggle in straightened condition during the initial part of a cycle of movement of the flywheel, and means for releasing the toggle, thereby to provide for movement of the block into engagement with the other stop.

4. In a one revolution type driving mechanism, a drive shaft, a hub on the shaft, a flywheel mounted coaxially of the shaft, a plurality of spaced stops carried by the flywheel, a block slidably mounted upon the flywheel for movement between the stops, a clutch part slidably mounted in the hub for movement into the path of movement of the block, resilient means normally operative to force the block toward one of the stops, and means for relieving the resilient means subsequently to engagement of the block with the clutch part thus to provide for movement of the block into positive engagement with the other of the stops.

5. In a one revolution type driving mechanism, a drive shaft, a hub on the shaft, a flywheel mounted coaxially of the shaft, a plurality of spaced stops carried by the flywheel, a block slidably mounted upon the flywheel for movement between the stops, a clutch part slidably mounted in the hub for movement into the path of movement of the block, resilient means normally operative to force the block into engagement with one of the stops, cam-controlled means for releasing the resilient means subsequently to engagement of the block with the clutch part to provide for movement of the block into positive engagement with the other of the stops, and means for rendering the resilient means again operative after a single revolution of the drive shaft.

6. In a one revolution type driving mechanism, a drive shaft, a hub on the shaft, a flywheel mounted coaxially of the shaft, a block slidably mounted on the flywheel for angular movement about the axes of the flywheel and shaft, a clutch part slidably mounted in the hub for movement into the path of movement of the block, a stop on the flywheel, a spring normally operative to force the block in a direction away from the stop and toward the clutch part when the latter is in the path of movement of the block, and means for relieving the spring to provide for positive engagement of the block with the stop.
